[57] **ABSTRACT**

A fluted disc is maintained concentrically within an internally serrated ring by a plurality of elastic cylinders disposed therebetween and positioned to provide a zero summation of forces through the central axis of the mechanism. The ring is fixed to the rotary device housing and a manually operable control shaft for the latter extends axially through the disc which is keyed for rotation with the shaft. Rotation of the disc rolls the elastic cylinders along the surfaces of the disc and ring to seat in the next adjacent flutes and serrations, respectively, the cylinders being compressed when passing over the ridges between adjacent flutes and serrations and rapidly restoring upon passing beyond the ridges to positively seat within the next flutes and serrations. The detent torque may be readily varied by increasing or decreasing the number of elastic cylinders. While mathematical and geometrical relationships are established to permit a detent mechanism to be provided for almost any rotary application, a primary relationship to be established in each instance requires that the chord length of the flutes be identically equal to the chord length of the serrations to permit continuous rotary operation.

PLANETARY DETENT FOR ROTARY DEVICES

BACKGROUND OF THE INVENTION

This invention relates to detent mechanisms particularly well suited for use with rotary devices such as rotary electrical switches or the like.

Detent mechanisms for rotary switches serve as indexing means for establishing positive contact engagement. Such mechanisms typically employ complementally formed recesses and projections which are biased into engagement by spring means. An operation of the switch causes the complemented formations to be cammed apart against the bias of the spring means and to re-engage with another complementally formed portion. The camming motion is usually in a direction normal to the travel of the movable member of the switch and introduces considerable sliding friction forces, wear and dust particle problems for the switch. The size of the switch establishes limits in size and strength of the spring means as well as in the size of the complemental portions, thereby limiting the torque which may be achieved by a given detent mechanism. Accordingly, prior art detent mechanisms have generally been custom designed for each specific application.

SUMMARY OF THE INVENTION

It is a primary object of this invention to provide a detent mechanism for use in a continuously rotating operational mode which operates totally without sliding friction in any force-loaded direction of the mechanism components.

It is a further object of this invention to provide a detent mechanism of the foregoing type which may be readily adapted to rotary devices of widely varying sizes.

It is a further object of this invention to provide a detent mechanism of the foregoing type wherein the operational torque may be simply and readily varied.

It is still another object of this invention to provide a detent mechanism of the foregoing type which may be readily and inexpensively manufactured.

These and other objects and advantages of this invention will become more readily apparent in the following specification and claims when read in conjunction with the appended drawings.

BRIEF DESCRIPTION OF THE DRAWINGS

FIG. 1 is a side elevational view of a rotary electrical switch incorporating the detent mechanism of this invention;

FIG. 2 is an enlarged cross-sectional view taken along the line 2-2 in FIG. 1 and showing the detent mechanism of this invention in elevation;

FIGS. 3a, 3b and 3c are elevational views of the detent mechanism of this invention showing modifications thereof;

FIGS. 4a, 4b and 4c are fragmentary views of portions of the detent mechanism sequentially depicting an operation of the mechanism; and

FIG. 5 is a fragmentary view of a portion of the detent mechanism of this invention with certain dimensional references applied thereto.

DESCRIPTION OF THE PREFERRED EMBODIMENTS

A one hole mounting rotary electrical switch 2 is shown in FIG. 1 of the drawings. The switch 2 includes a metallic frame 4 having a threaded mounting bushing 6 secured thereon. The detent assembly 8 of this invention and a rotary electrical switch deck 10 are secured in tandem to the rear of frame 4 by three screws 12 which project rearwardly through aligned openings in the frame 4, detent assembly 8 and switch deck 10 to receive nuts 14 thereon. The detent assembly 8 includes a cover plate 16 disposed between frame 4 and an outer track member 18 of the detent assembly and an insulating plate 20 disposed between the outer track member 18 and the switch deck 10.

Switch 2 further includes a centrally disposed axially extending operating shaft 22 which appears in cross-section in FIGS. 2 through 4c. While not specifically shown in the drawings, shaft 22 is journaled for rotation within frame 4 and bushing 6 to extend in opposite directions thereof, a first end extending beyond the outer end of bushing 6 to have a knob 24 secured thereto and the opposite end extending through detent assembly 8 into switch deck 10. The last mentioned end of shaft 22 is formed to have a square cross-sectional configuration to be cooperatively received within complementary shaped openings in a movable member of the detent assembly and in the rotary contact structure of switch deck 10 to operate the switch.

With particular reference to FIG. 2, the aforementioned outer track 18 may be seen to be a ring having a continuously serrated inner diameter 26. Outer track member is preferably formed of an electrical insulating material and is provided with three clearance holes 28 for screws 12. If desired the holes 28 may be formed substantially oversized for screws 12 and bushings 30 provided therein to aid in centering the detent on the rotary device in assembly if tolerances are not held closely.

Detent assembly 8 further includes a centrally located disc 32 also preferably formed of an electrical insulating material and having a continuously fluted periphery 34. Disc 32 is keyed for rotational movement with shaft 22 by means of a central square-shaped aperture 36 through which the square portion of shaft 22 extends. The thickness of disc 32 is somewhat less than that of outer track member 18 to permit free rotational movement of disc 32 between cover plate 16 and insulating plate 20.

A plurality of elastic cylinders 38 are positioned between the fluted periphery 34 of disc 32 and the serrated inner diameter 26 of ring shaped outer track 18 to rest within oppositely disposed ones of the flutes and serrations. As will be brought out later, certain of the oppositely disposed flutes and serrations cooperate to form opposed arcs on a common circle whose diameter is substantially identical to the diameter of each of said elastic cylinders 38. The exact number of elastic cylinders 38 used in a detent assembly varies according to the amount of torque desired for the operating shaft; where greater torque is required a greater number of elastic cylinders 38 are employed. Regardless of the number of cylinders employed, however, the same are always physically positioned within the detent assembly in a manner whereby the summation of the forces

presented by the cylinders through the central axis of shaft 22 is equal to zero. The exemplary detent in FIG. 2 employs three cylinders 38 spaced at 120 degree intervals. FIGS. 3a through 3c depict the same detent assembly employing two, four and six cylinders 38, respectively, the cylinders in each instance being equally arcuately spaced to provide a zero summation of forces through the central axis.

The particular detent assembly 8 shown in the drawings is designed to establish 45° indexing positions for shaft 22 and switch deck 10. With reference to FIGS. 4a—4c and particularly to FIG. 4a, a portion of the detent assembly is redrawn in enlarged scale to show the upper cylinder 38 of FIG. 2 and fragmentary portions of the serrated inner diameter 26, disc 32 and shaft 22. It is to be understood that the operational movement described in connection with the upper elastic cylinder 38 is simultaneously identical for each cylinder 38 employed.

An initial position of the shaft 22 and detent assembly 8 is shown in FIG. 4a wherein elastic cylinder 38 rests in a serration on inner diameter 26 defined by ridges S1 and S2 and in a flute on the periphery 34 of disc 32 defined by ridges F1 and F2. Rotation of the shaft 22 is a counter-clockwise direction as viewed in the drawings and indicated by arrow 40 drives disc 32 therewith by virtue of the aforescribed complementary square shapes of shaft 22 and aperture 36 in disc 32. Counter-clockwise movement of disc 32 rolls the elastic cylinder 38 along the periphery 34 and along the inner diameter 26 to cause the points F2 and S2 to imbed into and compress the cylinder 38 as shown in FIG. 4b. Maximum compression of the cylinder 38 is reached when the point F2 is rotated to fall on a common immaginary straight line through the point S2, the center of cylinder 38 and the axial center of the shaft 22. Continued rotation of disc 32 rotates the point F2 beyond the above described immaginary line and the elastic cylinder 38 begins to restore itself back to its original shape. The restoring force of cylinder 38 is exerted radially outwardly thereof against its points of contact S2 and F2 to provide a driving force in the counter-clockwise direction for disc 32.

Disc 32 continues to rotate until the point F3 of the next adjacent flute engages the periphery of the elastic cylinder 38 to establish a subsequent rest position for the detent as shown in FIG. 4c. In accordance with a novel feature of this invention, the point S3 of the next adjacent serration engages the periphery of elastic cylinder 38 simultaneously with the aforementioned engagement of point F3 therewith and the new rest position is positively established. With reference to FIG. 4c, it can be seen that in this position, the cylinder 38 now lies between the arcs bounded by points S2 and S3 on the inner diameter 26 and by points F2 and F3 on the periphery 34 of disc 32. The shaft 22 is now displaced 45° counter-clockwise from the initial position.

The simultaneous engagement of the points S3 and F3 with the elastic cylinder 38 permit the detent assembly 8 to be used in a continuously rotating mode without the disc and outer track getting out of synchronization. If the point S3 was not to engage the cylinder 38 when the latter seats firmly between the points F2 and F3, a small increment of travel of cylinder 38 along the serrated inner diameter 26 would

remain to be initially traversed during the next successive indexing movement of disc 32. It should be apparent that the remaining increment of travel is cumulative over the individual positions and that if similar conditions exist for each of the positions, successive indexing in a given rotational direction will cause the cylinder 38 to eventually straddle a ridge between adjacent serrations when it is firmly seated in a flute on disc 32, thereby causing the disc 32 to be out of synchronization with the outer track 18 and the switch deck 10. A similar situation exists when a small increment of overtravel is present between the cylinder 38 and a serration on the inner diameter 26.

A primary consideration in the design of the detent of this invention to render it particularly well suited for continuously rotating operation is the establishment of equal chord length between the chords 42 of the flutes on disc 32 and the chords 44 of the serrations on inner diameter 26. The chords 42 and 44 are shown in FIG. 5 as the opposite ends of a rectangle inscribed within the cylinder 38, thereby geometrically establishing their equal length. With the distances between the ridges of the flutes and serrations being equal, the elastic cylinder 38 will necessarily seat positively within the cooperating flute and serration and no overtravel or undertravel of the cylinder will be present.

In conjunction with the establishment of equal chord lengths, certain mathematical relationships are also provided which aid in constructing a detent mechanism for any given rotary device. Referring particularly to FIG. 5, a pair of lines are shown radiating from the rotational center of the detent mechanism to the opposite ridges of a flute on periphery 34 of disc 32 to define an included angle A therebetween. Similarly, a second pair of lines radiate from the center to the opposite ridges of a serration on inner diameter 26 to define an included angle B therebetween. From the sequential views of FIGS. 4a—4c and the description associated therewith, it can be seen that the total angular travel of shaft 22 and disc 32 per single indexing movement is equal to the sum of angles A and B. To be workable with a rotary device, the quotient of 360° divided by the sum of angles A and B must be a whole number. Additionally, it is apparent from FIG. 5 that angle A is greater than B and while the exact ratio of A to B may vary if necessary, it has been found most convenient to require A to be twice as great as B. Therefore, given a number of positions for a rotary device, the indexing angle and the angles A and B may be calculated.

Again referring to FIG. 5, it can be seen that the radial distances from the rotational center of the detent mechanism to the ridges of the flutes on disc 32 and serrations on inner diameter 26 are dimensioned as X and Y, respectively. Knowing the values for angles A and B and that chords 42 and 44 are equal, a relationship between X and Y can be geometrically shown to exist as $Y = \sin B/2/\sin A/2$. By choosing a value for X which physically adapts the mechanism to the size of the particular rotary device, a proportionate value of Y may be determined from the foregoing formula.

In the drawings, it can be seen that the flutes and serrations are preferably formed arcuately of a radius equal to the radius of the elastic cylinders 38, although they could be formed of a lesser radius or by V-shaped

notches if desired, so long as the distances between the adjacent ridges remained equal. The diameter D of the cylinder 38 is the diagonal of the inscribed rectangle shown in FIG. 5 and is provided by another geometrical relationship stated by the formula

$$D = n\sqrt{X^2 + Y^2 - 2XY \cos(A + B)/2}$$

The factor n is determined from a durometer reading giving the hardness of the material to be used for the cylinders 38 and increases the diameter D in inverse proportion to the hardness of the material. Thus, in addition to providing more elastic cylinders 38 as mentioned earlier, the torque may also be increased by providing larger and/or less resilient cylinders 38.

Thus there is provided herein a basic detent mechanism which may be used in a continuously rotating mode without getting out of synchronism, which operates solely with rolling friction and which may be readily and easily modified to increase or decrease the detent torque desired. In addition, the detent mechanism provided herein is a thin self-contained unit which may be readily added to a rotary device or may be easily incorporated as an integral portion of a rotary device. The mathematical relationships provided herein permit the basic operational design of the mechanism to be readily adopted to a wide range of rotary devices regardless of the number of positions required or physical size of the devices.

I claim:

1. A detent mechanism for use with a rotary device comprising, in combination:

a first member having a generally cylindrical internal surface and a plurality of inwardly projecting, axially extending ridges formed on said internal surface at equally spaced intervals therealong;

a second member having a generally cylindrical external surface and a plurality of outwardly projecting, axially extending ridges formed on said external surface at equally spaced intervals therealong disposed concentrically within said first member, the chord length between adjacent ridges on said second member being identically equal to the chord length between adjacent ridges on said first member;

a plurality of circular elastic members disposed between said first and second members each engaging at the periphery thereof with adjacent pairs of ridges on said first and second members;

means connecting one of said first and second members to a stationary portion of said rotary device and means connecting the other of said first and second members to a movable portion of said rotary device and to an operator means to effect rotational movement of said other member relative to said one member when operated, said movement causing said elastic members to roll

along said internal and external surfaces of said first and second members, respectively, to be compressed between cooperating ridges on said first and second members as the respective ridges become radially aligned and to sequentially expand as said ridges move beyond radial alignment, said elastic members engaging with succeeding adjacent pairs of ridges on said first and second members to establish a rotationally displaced position of one of said first and second members with respect to the other thereof.

2. The combination according to claim 1 wherein said elastic members are cylinders extending axially in directions parallel to said ridges.

3. The combination according to claim 2 wherein said ridges are formed by adjacent concave grooves formed in said internal surface of said first member and in said external surface of said second member, said grooves having a radius substantially equal to that of said elastic cylinders.

4. The combination according to claim 3 wherein said first member is connected to the stationary portion of said rotary device and said operator means for said rotary device is rotationally keyed to said second member to cause rotational movement thereof relative to said first member.

5. The combination according to claim 1 wherein:

A represents the included angle between a pair of imaginary lines radiating from the axial center of said second member to respective ones of an adjacent pair of ridges on the external surface of said second member;

B represents the included angle between a pair of imaginary lines radiating from the axial center of said first member to respective ones of an adjacent pair of ridges on the internal surface of said first member;

X represents the radial distance from the axial center of said first member to the ridges on the internal surface thereof;

Y represents the radial distance from the axial center of said second member to the ridges on the external surface thereof;

the sum of angles A and B is the indexing angle for the detent and is divisible into three hundred sixty to result in a whole number quotient; and said first and second members are constructed according to the relationship $Y \sin A/2 = X B/2$.

6. The combination according to claim 5 wherein D represents the diameter of said circular elastic members and is found by the formula

$$D = n\sqrt{X^2 + Y^2 - 2XY \cos(A + B)/2}$$

where n is a factor determined from the hardness of the material of said elastic cylinder and increases the diameter D inversely to increasing hardness of the material.
